INDEXING AND LOCK MECHANISM

Otto H. Pearson, Salt Lake City, Utah, assignor
to Louis N. Strike, Salt Lake City, UtahOriginal application April 2, 1945, Serial No.
586,053. Divided and this application Decem-
ber 12, 1946, Serial No. 715,689

2 Claims. (Cl. 192—139)

1

This application relates to shirt pressing machines and deals more particularly with a mechanism for indexing and locking rotatable means embodying a pair of bucks. This application is a division of my co-pending application entitled Shirt Pressing Machine, Serial Number 586,053, and filed April 2, 1945.

The machine disclosed in the co-pending application is provided with two bucks mounted on a revoluble column, one on either side thereof, for alternate positioning of said bucks with relation to a pressing head, whereby the bosom or front portion of a shirt draped over each buck is pressed between said pressing head and the shirt draped buck. Steam for the pressing operation is admitted to the bucks through said column and to the pressing head.

The present invention has for its primary object to provide improved means for positioning the bucks alternately for pressing engagement with the pressing head, for locking the buck carrying means in said position of a buck, and to initiate movement of the pressing head toward the buck.

Another object of the invention is to provide rotary means of the character indicated which is self-locking upon attaining a desired position and which is adapted to be released by independently operated means.

Another object of the invention is to provide rotatable means which is adapted to be locked by a toggled operated mechanism controlled by a member on the rotatable means.

A further object of the invention is to provide, in means of the character indicated, improved anti-friction support means for a rotary buck carrying member.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is an elevational view, partly in section, of indexing and locking mechanism embodying the present invention.

Fig. 2 is a cross-sectional view as taken on the line 2—2 of Fig. 1.

2

Fig. 3 is an enlarged cross-sectional view as taken on the line 3—3 of Fig. 1.

The indexing and locking mechanism shown in the drawing comprises, generally, a machine frame 5, a fixed support base 6 mounted on the frame, a rotary base 7 on the fixed base, means 8 for locking the bases together, toggle means 9 for operating the locking means 8, means 10 on the rotary base 7 for actuating the toggle means 9, means 11 controlled by movement of the toggle means to initiate movement of a pressing head, and means 12 for moving the locking means 8 to non-locking position.

As shown, the machine frame 5 consists of a pair of side frame members 15 suitably spaced to support the fixed base 6 thereon and to contain the means 8, 9, 11 and 12 therebetween.

The base 6 is shown as a generally circular plate 16 of suitable strength to support the means 7. As contemplated, the base plate 16 is provided with an eccentrically placed hole or passage 17 which is formed in a guide bushing 18 extending through the plate. Centrally, the plate fixedly mounts an upwardly extending hollow member 19 to which is connected a pipe 20 whereby steam for pressing purposes is admitted to said member 19. The top surface of the plate 16 is formed with a raceway near its peripheral edge for a plurality of bearing balls 21.

The rotary base 7 comprises a grooved pulley 22 and a plate 23 secured thereto, both being centrally and axially aligned with the base plate 16. The plate 23 is also formed with a raceway for said bearing balls 21, the latter supporting the base 7 for free rotation with respect to the base plate 16. A hollow column 24 is fixed to the pulley 22 to extend upwardly therefrom around the fixed hollow member 19 and to receive steam from the pipe 20. Although not shown, the column 24 carries a pair of diametrically opposed bucks disclosed in the mentioned co-pending application, said bucks receiving steam from the column. A suitably driven belt 25 engaged in the groove of pulley 22, rotates the base 7 in the direction of the arrow 26.

The means 8 comprises a locking pin 27 having a conical upper end and guided for vertical movement in the bushing 18, and a bar 28 pivotally connected at 29 to the lower end of the pin 27. The lower end of the bar 28 carries a plate 30 pressed by a spring 31.

The toggle means 9 includes an arm 32 pivotally mounted at 33 on bracket ears 34 of a plate 35. The latter is secured to the under face of the base plate 16 and is provided with a second pair of bracket ears 36 for a rotatable pin 37 having a transverse passage therethrough. A toggle link 38 extends through said passage and

pivotedly connects at 39 to one end of the arm 32. A compression toggle spring 40 is arranged about the link 38 and has end abutment with the pin 37 and a shoulder 41 on said link. A pivot connecting pin 42 extends through the arm 32 and the locking pin 27 in such a manner that the latter is held depressed when the toggle 9 is in the full line position of Fig. 1 and is raised into one of a pair of recesses 43 in the pulley 22. Said recesses are diametrically placed so that said locking pin engages one of them for each one-half rotation of the base 7.

The means 10 comprises a pair of diametrically positioned cam lugs 44 on the base 7 and suitably oriented with respect to the recesses 43. A roller 45 is carried by the arm 32 of the toggle means 9 in the path of movement of the cam lugs 44 so that the latter, as seen in Fig. 2, engages the roller to press the same outwardly with a resultant breaking of the toggle between the arm 32 and link 38 and thereby causing the locking pin 27 to be raised against the under surface of plate 23 and to, subsequently, fall into one of the recesses 43 and effect firm locking of the bases 6 and 7.

The means 11 comprises a valve 46 carried by an extension 47 of one bracket ear 34, and a valve operating pin 48 cushioned by a spring 49 carried for movement in a guide boss 50 on an extension 51 of the toggle arm 32. Outward movement of the roller 45, as mentioned, will move the pin 48 to engage and press a rod 52 and a piston 53 on the latter to open an air line 54 employed for effecting movement of the mentioned pressing head toward a buck aligned therewith.

The means 12 is more fully disclosed in the co-pending application. In the drawing, said means is merely shown as an arm 55 fulcrumed at 56 on the frame sides 15 and bifurcated at its outer end 57 to engage along either side of the bar 28. A transverse pin 58 carried by the bifurcation holds said bar captive. The means 12 is normally in the full line position, permitting the toggle means 9 to raise the locking pin 27, the spring 34 yielding to the force of the toggle spring 40. When release or depression of the pin 27 is desired, suitable means moves the arm 55 to the dot-dash line position to withdraw the pin and thereby release the base 7 for rotation.

In operation, with the base 7 normally locked and holding the mentioned bucks stationary so that a garment on one is being pressed and a garment is being placed on the other, the means 12 is then actuated to withdraw the pin 27. The base 7 is then free to be rotated, as indicated, by the belt 25. The means 12 is then restored to the full line position. One of the cam lugs 44, as the end of a half rotation of the base is approached, encounters the roller 45 and actuates the toggle means 9 to raise the pin 27 into the recess 43 associated with the latter cam lug. The base 7 is held stationary and the belt slips in the groove of the pulley. The pressing operation on one buck and the garment donning operation on the other is effected during the stationary period of base 7. The means 12 is then again moved to withdraw the locking pin 27 for continued rotation of the base 7 in the same direction to bring the pressed garment to the operator and the newly donned garment to pressing position. The operation continues as described.

While I have illustrated and described what I now regard as the preferred embodiment of my invention, the construction is, of course, subject to modifications without departing from the spirit

and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. Indexing and locking mechanism comprising a fixed base having a guide passage therethrough, a rotary base mounted on and concentric with the fixed base and having a pair of diametrically opposed seats for alternate alignment with said guide passage, a locking member in the guide passage, a pair of spaced brackets depending from the fixed base and radially arranged with respect to the axis of rotation of the rotary base, an over-center toggle extending between and carried by said brackets and including a lever connected to the locking member, a roller carried by one end of said lever, said toggle, in one position thereof, holding said locking member withdrawn from engagement with the seats of the rotary base and also holding said roller in close proximity to the peripheral edge of said rotary base, and a pair of diametrically opposite cam lugs on the periphery of said rotary base and oriented with the seats therein to alternately engage said roller and move the lever thereof to break the toggle and project the locking member into said seats alternately.

2. Indexing and locking mechanism comprising a fixed base having a guide passage therethrough, a rotary base mounted on and concentric with the fixed base and having a pair of diametrically opposed seats for alternate alignment with said guide passage, a locking member in the guide passage, a pair of spaced brackets depending from the fixed base and radially arranged with respect to the axis of rotation of the rotary base, an over-center toggle extending between and carried by said brackets and including a lever connected to the locking member, a roller carried by one end of said lever, said toggle, in one position thereof, holding said locking member withdrawn from engagement with the seats of the rotary base and also holding said roller in close proximity to the peripheral edge of said rotary base, a pair of diametrically opposite cam lugs on the periphery of said rotary base and oriented with the seats therein to alternately engage said roller and move the lever thereof to break the toggle and project the locking member into said seats alternately, a bar pivotally connected to and depending from the locking member, a resiliently mounted plate on the lower end of said bar, and a bifurcated actuator through which said bar extends and movable to engage said plate to effect withdrawal of the locking member and return of the roller to proximity with the periphery of the rotary base.
